THEFTPROOF LAMP SOCKET

Leonard Delano, Minneapolis, Minn.

Application February 8, 1940, Serial No. 317,880

7 Claims. (Cl. 173—356)

My invention relates to sockets for electric light bulbs and particularly to sockets arranged to prevent theft of lamp bulbs therefrom.

Much difficulty and expense has been occasioned due to theft of electric light bulbs from lamp sockets of conventional design situated in places accessible to the public such as public telephone booths, halls and toilet rooms of public buildings and apartment buildings, and the like. To prevent such thefts lamp guards which are locked onto sockets have been used and various types of special lamp sockets have been devised.

Lamp sockets have been devised wherein lamps are retained by means which are releasable by suitable application of keys or tools thereto and such sockets work in the same manner regardless of whether the lamps therein are burned out or are in operable condition. Such sockets have the disadvantage that the necessary key or tool may be lost or not at hand when a change of lamps becomes necessary.

A general object of my invention is to provide a lamp socket from which a burned out lamp may be easily removed without the use of a key or tool and from which an operable lamp cannot be removed.

A more specific object is to provide such a socket including in its structure means preventing removal of an operable lamp from the socket associated with electrical means capable of being brought into action from outside the socket and capable of distinguishing between a burned out lamp and an operable lamp to permit removal of only a burned out lamp.

Another object is to provide such a socket including a screw base lamp socket mounted in a socket case for rotation relative thereto about the axis of the socket element so that the socket element will tend to turn with a lamp bulb which is in engagement with the screw threads of the socket element and being rotated relative to the socket case.

Still another object is to provide such a socket including means limiting rotation of the socket element responsive to screwing of a lamp thereinto but permitting rotation of the socket responsive to an attempt to unscrew a lamp therefrom.

Yet another object is to provide such a socket having normally inoperative means for limiting rotation of the socket responsive to unscrewing rotation of a lamp in the socket relative to the socket case controlled by electromagnetic means brought into action by a switch manipulatable

from outside the socket case to render said rotation limiting means operative if the lamp in the socket is burned out and leave said rotation limiting means inoperative if the lamp in the socket is in operable condition.

A further object is to provide such a lamp socket of which all the rotation controlling parts and the socket element are sufficiently compact to enable housing of the same in a socket case of dimensions not exceeding the dimensions of the case of a conventional lamp socket to an impractical extent.

A still further object is to provide such a theft-proof lamp socket of light, simple, rugged, reliable and inexpensive construction.

These and other objects and advantages of the invention will more fully appear from the following description made in connection with the accompanying drawing, wherein like reference characters refer to the same parts throughout the views, and, in which:

Fig. 1 is a longitudinal sectional view of a theftproof lamp socket which constitutes an embodiment of my invention;

Fig. 2 is a sectional view taken on the line 2—2 of Fig. 1;

Fig. 3 is a partial side view;

Fig. 4 is an exploded view of a group of movable elements employed in the socket rotation controlling mechanism of my theftproof socket; and

Fig. 5 is an electrical connection diagram of the socket element, electromagnetic control means and electrical switching means of my theftproof lamp socket.

Referring to the drawing, I provide a socket case 10 consisting of a tubular body portion 10a and a cap portion 10b which may be constructed in the same manner as a conventional lamp socket case and in which the body 10a and cap 40 10b may be connected together in the same manner as the corresponding parts of a conventional lamp socket case. However, the dimensions of my socket case 10 are somewhat greater than those of the conventional lamp socket case so as to accommodate the parts contained therein and which will be described.

In the lower and open end of the case 10, I provide a lamp socket 11 of the Edison or screw base type supported within the lower portion of the case 10 for rotation relative thereto about the common axis of the case 10 and socket element 11. The socket element includes an electrically conductive screw shell 11a similar to that of the ordinary lamp socket and having an 55

inwardly flanged upper end to which a centrally apertured disc 11b is secured by suitable means such as the rivets 11c. On the lower side of the center of the disc 11b I provide a center electrical contact button 11d corresponding to the center contact button of the ordinary lamp socket and formed in a manner to be described.

For rotative mounting of the socket element 11 I provide a shaft 12 disposed thereabove in co-axial relation therewith. The lower end of the shaft 12 is made to reduced diameter, is extended downwardly through the apertured central portion of the disc 11b and is peened or riveted at its lower end to secure the disc 11b 5 of the socket element 11 to the lower end of the shaft 12 and form the center contact button 11d of the socket element 11 as shown. Thus the shaft 12 and socket element 11 are non-rotatively connected for rotation together as a unit.

20 The shaft 12 is journaled and in electrical contact with an electrically conductive and preferably but not necessarily non-magnetic sleeve 13 which constitutes a stationary bearing for the shaft 12 and electrical terminal for the center contact button 11d of the rotatable socket element 11. The lower end of the sleeve 13 and the disc 11b of the socket element 11 are spaced apart by a collar 14 formed of electrical insulating material and associated with the lower 25 portion of the shaft 12 in closely encircling relation therewith. The upper end of the shaft 12 is of reduced diameter and the upper limit of the full diameter portion of the shaft 12 is approximately flush with the upper end of the 30 sleeve 13. A centrally apertured disc 15 of electrical insulating material is fixedly mounted on the lower extremity of the sleeve 13 by suitable means such as by screw threading the sleeve 13 and disc 15 as indicated in Fig. 1 of the drawing. A helical spring 16 is placed in encircling 35 relation with the insulating collar 14 and interposed between the insulating disc 15 and flanged upper end of the screw shell 11a of the socket element 11 in partially compressed condition so as to be in firm electrical contact with the screw shell 11a of the rotatable socket element 11 to provide a stationary electrically conductive means connected with the screw shell 11a in a manner not interfering with rotation of the 40 socket element 11. The wire of which the spring 16 is formed is extended to form an electrical conductor 16a running along the inner side of the tubular socket case member 10a to the upper portion of the interior space of the socket 45 case 10. The electrical conductor 16a may, of course, be provided with an electrical insulating covering in any suitable conventional manner to prevent undesired electrical contact thereof with other parts of my device.

50 A short distance below the upper end of the sleeve 13 a centrally apertured electrically conductive plate 17 is fixed thereon in encircling relation therewith in a plane normal to the common axis of the sleeve 13 and socket case 10. 55 Immediately below the plate 17 a centrally apertured disc 18 is placed on the sleeve 13. Between the insulating discs 15 and 18 an electromagnetic coil M is wound on the sleeve 13 and the shaft 12 constitutes a magnetic core for the coil M. 60 for a purpose to be later explained. The coil M is wound for use as a potential coil to be operated on the same voltage as a lamp to be placed in the socket element 11.

A second electromagnetic coil S is provided in 65 upwardly spaced and co-axial relation with the

first coil M and has therewithin a magnetic core 19 disposed co-axially of the shaft 12 and having a lower end spaced a short distance above the upper end of the shaft 12. A pair of upstanding posts 20 formed on the right-hand portion of the plate 17 and another pair of upstanding posts 21 formed on the left-hand portion (as viewed in Fig. 1) of the plate 17 engage, at their upper ends, the lower side of the upper electromagnetic coil S to maintain the same in a fixed spaced 10 relation with the plate 17. The coil S is wound for connection in series with a lamp carried in the socket element 11 to operate on current passing through the coil S to such lamp.

Above the upper coil S I provide a spring return, single pole, double throw electrical switch 22, which may be of any suitable conventional construction and which includes an operating button 22a therefor which projects through a suitably apertured portion of the tubular socket case member 10a to a point outside thereof as indicated in Fig. 1. As in any conventional type of socket I provide for bringing an electrical cord such as the cord 23 into the upper end of the interior space of the case 10 for connection 25 of the individual electrical conductors 23a and 23b thereof to suitable terminals of my device. The electrical connections between the cord 23, the switch 22, the coils S and M and the socket element 11 are diagrammatically shown in Fig. 5 30 and may be formed of suitable electrical conductors of conventional type installed in my device in a conventional manner. As indicated in Fig. 5, the electrical cord conductor 23a is connected to the conductor 16a leading to the 35 screw shell 11a of the socket element 11 and to one terminal of the coil M. The conductor 23b is connected to the movable contact element 22b of the switch 22 and to one terminal of the coil S. The remaining terminal of the coil S is connected to the stationary contact element 22c of the switch 22 which is normally engaged by the movable switch contact element 22b and is also connected to the plate 17 and accordingly through the sleeve 13, and the shaft 12 to the center 40 contact button 11d of the socket element 11. The switch contact element 22d, which is normally not in engagement with the movable switch contact element 22b is connected to the remaining terminal of the coil M. From the above it 45 should be seen that the coil S is connected in series with the socket element 11 but is normally shunted by the normally interengaged switch contact elements 22b and 22c, and that the coil M is so connected as to normally be 50 de-energized. Shifting of the movable switch contact element 22b from normal position to operated position will first unshunt the coil S to cut the same in series with a lamp in the socket element 11 by separating the switch contact 55 elements 22b and 22c and then will engage switch contact element 22b with switch contact element 22d to connect the coil M across the supply line 60 constituted by the conductors 23a and 23b of the cord 23. Terminal screws shown in Fig. 1 may 65 be provided for connection of the cord conductors 23a and 23b thereto and will, of course, be connected in turn to the above described electrical circuit elements of my device in accordance with the electrical connection diagram of Fig. 5 and 70 the above explanation thereof.

A centrally apertured control disc 26, best shown in Fig. 4, is placed on the reduced diameter upper end of the shaft 12 and is fixed on the shaft 12 by peening or riveting the reduced 75

diameter upper end of the shaft 12 over the central portion of the upper side of the control disc 26. The control disc 26 constitutes a portion of the electromagnetically controlled mechanism which I provide for controlling rotation of the shaft 12 and the socket element 11 and is arranged for cooperation therewith of other elements by providing diametrically opposite rectangular notches 26a therein as shown in Fig. 4. One notch 26a would provide for the intended operation of my device but I prefer to provide two notches 26a, and, if desired, could provide a larger number. Of the nearly radial edges of the disc 26 defining each notch 26a, I bevel, as shown, the lower side of the one nearly radial edge situated at the right-hand side of the left-hand notch 26a of the disc 26 as viewed in Fig. 4 to form an inclined camming surface 26b. The remaining nearly radial edge 26c is purposely not bevelled and constitutes an abutment surface.

I provide means co-acting with the control disc 26 to limit rotation of the socket element 11 such as would be caused by an attempt to screw a lamp into the socket element 11. For this purpose I provide a flat, resilient, annular, upwardly pressing spring 27, best shown in Fig. 4, disposed in encircling relation with the upper end portion of the bearing sleeve 13. At one side of the annular spring the same is extended outwardly to form an apertured mounting ear 27e which, as seen in Fig. 1, is placed on the left-hand portion of the plate 17 and is fixedly secured thereto by suitable means such as the rivets 27f. Diametrically opposite the mounting ear 27e, that is at the deflectible free edge portion of the spring 27, the spring 27 has secured on the upper side thereof, as best seen in Fig. 4, a pawl block 27a extending radially across and outwardly beyond the free end portion of the spring 27, the portion of the block 27a overlying the spring 27 being disposed at the same radius from the axis of the shaft 12 as the notches 26a of the control disc 26 and being bevelled, as shown in Fig. 4, on the nearest (as viewed in Fig. 4) upper corner to form an inclined camming surface 27b for co-operation with the inclined camming surfaces 26b of the notched portions of the control disc 26. The edge of the block 27a opposite the bevelled portion 27b thereof is left unbevelled to constitute an abutment surface 27c. Due to the upwardly pressing construction of the spring 27 the inner portion of the block 27a is pressed against the lower side of the control disc 26 and, as the disc 26 is rotated, the block 27a moves upwardly into a notch 26a of the control disc 26 when the notch 26a becomes disposed above the block 27a. When the control disc 26 is rotating in the direction in which the socket element 11 would be carried by an attempted screwing of a lamp into the socket element 11, engagement of the block 27a in one of the notches 26a would result in interengagement of the abutment surfaces 26c and 27c of the control disc 26 and the block 27a to prevent further rotation of the socket element 11 and thus enable screwing of the lamp into the socket element 11. To restrain the spring 27 and block 27a from displacement circumferentially of the spring 27 the outer portion 27d of the block 27a is disposed between the upstanding elements 20 which are spaced apart to closely receive the block portion 27d for guiding the same in vertical movement and restraining the same from movement circumferentially of the annular spring 27. When the control disc is rotating in the direction correspond-

ing to the direction in which the socket element 11 would be rotated responsive to an attempt to unscrew a lamp from the socket element, the block 27a will raise into a notch 26a of the control disc 26 each time a notch 26a is over the block 27a but the camming surfaces 26b and 27b of the control disc 26 and the block 27a will interact to force the block 27 downwardly out of the notch 26a so that there will be no restraint of rotation of the control disc 26 and the socket element 11 to permit unscrewing of a lamp from the socket element 11. Thus rotation of a lamp in the socket element 11 in a direction intended to bring about unscrewing of the lamp from the socket element 11 will merely result in the socket element 11 rotating with the lamp to defeat removal of the lamp from the socket element 11.

I provide means, partially described above, for enabling limiting of rotation of the socket element 11 when an attempt is made to unscrew a burned out lamp from the socket element 11 and which will not act to limit rotation of the socket element 11 when an attempt is made to remove an operable lamp from the socket element 11. For this purpose I provide a vertically deflectible magnetic armature 28 above the control disc 26 and between the electromagnet poles constituted by the upper end of the shaft 12 and the lower end of the core 19 of the upper electromagnet S. As best seen in Fig. 4, the armature 28 has, on one end thereof a pair of lugs 28a apertured to accommodate a pivot pin. At the left-hand (as viewed in Fig. 1) side of the plate 17 the same is provided with an upstanding member 29 to the upper end of which the armature pivot lugs 28a are pivotally connected by means of a pivot pin 30 so that the armature 28 is mounted for vertical swinging movement between the upper end of the shaft 12 and the lower end of the magnet core 19 in response to magnetization of one or the other thereof. The free end portion 28b of the armature 28 is narrowed, as shown in Fig. 4, so that the same may be disposed between the vertical posts 20 to be guided thereby in vertical movements and to be restrained thereby from any appreciable sideward movement. A very light spring 31 is provided as shown in Fig. 1 to normally maintain the armature 28 in an upwardly deflected position thereof. In position for co-operation with the notched portions of the control disc 26 when the armature 28 is deflected downwardly out of its normal upwardly deflected position, the armature 28 is provided with a stop element 28c which, as best seen in Fig. 4, projects from the free end portion of the armature 28, at the nearest side thereof as viewed in Fig. 4, laterally and downwardly on an incline for a short distance and then laterally for a short further distance. The lower corner of the end edge of the stop element 28c is bevelled as shown in Fig. 4. The stop element 28c is so made as to be disposed slightly above the control disc 26 when the armature 28 is in its normal upwardly deflected position.

When it is desired to attempt to remove a lamp from the socket element 11 the lamp is rotated in a direction intended for unscrewing of the lamp and at the same time the switch 22 is shifted into and held in its operated position to first cut the coil S in series with the lamp socket element 11 and then connect the coil M to the line conductors 23a and 23b. If the lamp in the socket element 11 is in operable condition, cutting of coil S in series with the socket element 11 will result in current flowing through the coil S

whereby the core 19 thereof will be magnetized to hold the armature 28 in its normal upwardly deflected position so that subsequent energization of the coil M, when the switch 22 reaches its fully operated position, to magnetize the shaft 12 will not be effective for pulling the armature 28 into its operated position. Consequently the stop element 28c will remain in a position above the control disc 26 and rotation of the lamp will result in unrestrained rotation of the socket element 11 to defeat removal of the lamp from the socket element 11. If the lamp happens to be burned out or otherwise open circuited, the series coil S will not be energized by operation of the switch 22 since there will be no current flowing through the coil S to the burned out lamp and consequently the only opposition to movement of the armature into operated position will be the very light spring 31 which is purposely made too weak to prevent deflection of the armature 28 responsive to magnetization of the shaft 12 by energization of the coil M. When the switch 22 reaches its fully operated position, the coil M will be energized to magnetize the shaft 12 which will then deflect the armature 28 downwardly without opposition from the coil S. As the control disc 26 is rotated, one of the notches 26a thereof will reach a position under the stop element 28c of the armature 28 and the stop element 28c will drop into the notch 26a due to the magnetic pull of the magnetized shaft 12. Further rotation of the control disc through a slight angle will result in the free end portion of the stop element 28c becoming disposed under a portion of the control disc 26 adjoining the notch 26a and an edge 26b of the disc 26 partially defining the notch 26a abutting the medial portion of the stop element 28c to prevent further rotation of the control disc 26 and the socket element 11 so that the lamp may be unscrewed from the socket element 11. After the free end portion of the stop element 28c has reached a position under part of the control disc 26 it is no longer necessary to hold the switch 22 in operated position for the reason that the armature cannot then rise since the free end of the stop element 28c is in engagement with the lower side of the control disc 26. Thus it is seen that my theftproof socket device permits removal therefrom of a burned out lamp but defeats removal therefrom of an operable lamp.

When a new lamp is to be screwed into the socket element 11, the socket element 11 will, at first, rotate with the lamp. This rotation of the lamp socket element 11 will rotate the control disc in such direction that the free end of the stop element 28c of the armature 28 will disengage from the control disc 26 whereupon the spring 31 will return the armature 28 to its normal upwardly deflected position. Further rotation of the control disc 26 will bring into play the block 27a on the spring 27 to limit rotation as previously described and thus enable screwing the lamp into the socket element 11.

Since energization of the coil M is required in enabling removal of a lamp from my device it should be apparent that a lamp cannot be removed from my device when the supply of electrical current to the entire device is shut off as by means of a lighting switch in the circuit from which the cord 23 runs or a switch incorporated in the device ahead of the switch 22.

Attention is called to the fact that the switch contact 22c may be omitted from the switch 22 so as to leave the coil S permanently unshunted

in cases where the voltage drop caused by the impedance of the coil S would not be objectionable. Also it is possible to omit the switch 22 entirely so as to leave the coils S and M permanently in series and parallel respectively with the circuit to the socket element 11 if the relative strengths of the coils S and M are such that the coil S, when energized, is sufficiently strong to attract the armature 28 away from the coil M.

If my device is used in an inverted position it is, of course, feasible to omit the spring 31 and permit the pull of gravity to take care of the function ordinarily provided by the spring 31.

It is apparent that I have invented a novel, effective, light, compact, reliable and inexpensive theftproof electric lamp socket permitting installation of a lamp therein, capable of preventing removal of an operating lamp therefrom, and arranged to enable removal of a burned out lamp therefrom by a single and easy manipulation which is performed without the use of any kind of a key or tool.

It will, of course, be understood that various changes may be made in the form, details, arrangement and proportions of the various parts without departing from the scope of my invention.

What is claimed is:

1. An electric lamp socket device for preventing removal of an operable electric lamp bulb therefrom comprising, an open ended casing, an electric lamp socket having the usual screw threaded lamp receiving element and being mounted in the open end of said casing for rotation about the axis of said socket, means limiting rotation of said socket with a lamp being screwed therewith and permitting opposite rotation of said lamp socket, normally inoperative mechanism for limiting said opposite rotation of said socket, an electromagnetic armature included in said mechanism and constituting a control element therefor shiftable between actuated and unactuated positions whereby said mechanism is rendered respectively operative and inoperative, a first electromagnet connected in series with said socket and associated with said armature for operation to hold the same in unactuated position, and a second electromagnet connected in parallel with said socket and associated with said armature for operation to tend to pull said armature into its actuated position, said first electromagnet being of sufficiently greater strength than said second electromagnet to be capable of attracting said armature away therefrom.

2. An electric lamp socket device for preventing removal of an operable electric lamp bulb therefrom comprising, an open ended casing, an electric lamp socket having the usual screw threaded lamp receiving element and being mounted in the open end of said casing for rotation about the axis of said socket, means limiting rotation of said socket with a lamp being screwed therewith and permitting opposite rotation of said socket, normally inoperative mechanism for limiting said opposite rotation of said socket, an electromagnetic armature included in said mechanism and constituting a control element therefor shiftable between actuated and unactuated positions whereby said mechanism is rendered respectively operative and inoperative, relatively weak yieldable means for normally maintaining said armature in its unactuated position, a first electromagnet connected in series with said socket and associated with said armature for operation to

hold the same in unactuated position, and a second electromagnet connected in parallel with said socket and associated with said armature for operation to tend to pull said armature into its actuated position, said first electromagnet being of sufficiently greater strength than said second electromagnet to be capable of attracting said armature away therefrom.

3. An electric lamp socket device for preventing removal of an operable lamp bulb therefrom comprising, an open ended casing, an electric lamp socket having the usual screw threaded lamp receiving element and being mounted in the open end of said casing for rotation about the axis of said socket, means limiting rotation of said socket with a lamp being screwed thereinto and permitting opposite rotation of said socket, normally inoperative mechanism for limiting said opposite rotation of said socket, an electromagnetic armature included in said mechanism and constituting a control element therefor shiftable between actuated and unactuated positions whereby said mechanism is rendered respectively operative and inoperative, relatively weak yieldable means for normally maintaining said armature in its unactuated position, a first electromagnet connected in series with said socket and associated with said armature for operation to hold the same in unactuated position, a second electromagnet connected in parallel with said socket and associated with said armature for operation to tend to pull said armature into its actuated position, and spring return electrical switching means normally maintaining said second electromagnet disconnected, said switching means being operable from outside said casing to connect said second electromagnet.

4. An electric lamp socket device for preventing removal of an operable lamp bulb therefrom comprising, an open ended casing, an electric lamp socket having the usual screw threaded lamp receiving element and being mounted in the open end of said casing for rotation about the axis of said socket, means limiting rotation of said socket with a lamp being screwed thereinto and permitting opposite rotation of said socket, normally inoperative mechanism for limiting said opposite rotation of said socket, an electromagnetic armature included in said mechanism and constituting a control element therefor shiftable between actuated and unactuated positions whereby said mechanism is rendered respectively operative and inoperative, relatively weak yieldable means for normally maintaining said armature in its unactuated position, a first electromagnet associated with said armature for operation to hold said armature in unactuated position, a second electromagnet associated with said armature for operation to tend to pull said armature into actuated position, said first electromagnet being connected in series with said socket and said second electromagnet being connected in parallel with said socket, and spring return electrical switching means normally shunting said first electromagnet and maintaining said second electromagnet disconnected, said switching means being operable from outside said casing to unshunt said first electromagnet and connect said second electromagnet.

5. An electric lamp socket device for preventing removal of an operable lamp bulb therefrom comprising, an open ended casing, an electric lamp socket having the usual screw threaded lamp-receiving element and being mounted in the open end of said casing for rotation about the

axis of the socket, a disc having an eccentrically situated recess therein, said disc being disposed co-axially of said socket and mechanically connected thereto in non-rotative relation therewith, means associated with said disc for cooperating with the recessed portion thereof to limit rotation of said socket with a lamp being screwed thereinto and permit opposite rotation of said socket, an electromagnetic armature situated adjacent said disc and having a portion engageable in said recess when said armature is in actuated position to limit said opposite rotation, relatively weak yieldable means for normally maintaining said armature in an unactuated position thereof, a first electromagnet connected in series with said socket and associated with said armature for operation to hold the same in unactuated position, a second electromagnet connected in parallel with said socket and associated with said armature for operation to tend to pull the same into actuated position, and spring return electrical switching means normally maintaining said second electromagnet disconnected, said switching means being operable from outside said casing to connect said second electromagnet.

6. An electric lamp socket device for preventing removal of an operable lamp bulb therefrom comprising, an open ended casing, an electric lamp socket having the usual screw-threaded lamp-receiving element and being mounted in the open end of said casing for rotation about the axis of the socket, a disc having an eccentrically situated recess therein, said disc being disposed co-axially of said socket and mechanically connected thereto in non-rotative relation therewith, means associated with said disc for co-operation with the recessed portion thereof to limit rotation of said socket with a lamp being screwed thereinto and permit opposite rotation of said socket, an electromagnetic armature situated adjacent said disc and having a portion engageable in said recess when said armature is in actuated position to limit said opposite rotation, relatively weak resilient means for normally maintaining said armature in an unactuated position thereof, a first electromagnet connected in series with said socket and associated with said armature for operation to hold the same in unactuated position, a second electromagnet connected in parallel with said socket and associated with said armature for operation to tend to pull said armature into its actuated position, and spring return electrical switching means normally shunting said first electromagnet and maintaining said second electromagnet disconnected, said switching means being operable from outside said casing to unshunt said first electromagnet and connect said second electromagnet.

7. An electric lamp socket device for preventing removal of an operable lamp bulb therefrom comprising, an open ended casing, an electric lamp socket having the usual screw-threaded lamp-receiving element and being mounted in the open end of said casing for rotation about the axis of the socket, a disc having a rectangular notch in the marginal portion thereof, said disc being disposed co-axially of said socket and mechanically connected thereto in non-rotative relation therewith, means co-operating with the notched portion of said disc to limit rotation of said socket with a lamp being screwed thereinto consisting of a rectangular element situated and proportioned to fit in the notched portion of said disc and resilient means carrying said rectangular element and pressing the same toward said disc,

the corner of said rectangular element toward said disc and toward the direction of said rotation being bevelled to form a camming surface, the edge of said disc partially defining said notch 5 and facing opposite said direction of rotation being bevelled at the corner thereof nearest said rectangular element to form a camming surface for co-operation with said first-mentioned camming surface to cam said rectangular element 10 out of said notch responsive to rotation of said disc in a direction opposite to the direction of said first-mentioned rotation, an electromagnetic armature situated adjacent said disc and having a portion engageable in said notch when said

armature is in actuated position to limit said opposite rotation, relatively weak resilient means urging said armature toward an unactuated position thereof, a first electromagnet connected in series with said socket and associated with said armature for operation to hold the same in unactuated position, a second electromagnet connected in parallel with said socket and associated with said armature for operation to pull the same into actuated position, and means normally rendering said electromagnets ineffective but operable from outside said casing to render said electromagnets effective.

LEONARD DELANO.
